DESIGN FOR A COCKTAIL FORK

Aaron H. Fishman, Brooklyn, N. Y., assignor to Eagle Roll Leaf Stamping Company, Brooklyn,
N. Y.

Application November 20, 1947, Serial No. 142,682

Term of patent 3½ years

(Cl. D44—29)

To all whom it may concern:

Be it known that I, Aaron H. Fishman, a citizen of the United States, residing at Brooklyn, New York, in the county of Kings and State of New York, have invented a new, original, and ornamental Design for a Cocktail Fork, of which the following is a specification, reference being had to the accompanying drawing, forming a part thereof.

In the drawing:

Fig. 1 is a perspective view of a cocktail fork, showing my new design;

Fig. 2 is a side elevational view of same;

Fig. 3 is a transverse sectional view taken on the line 3—3 of Fig. 1; and

Fig. 4 is a bottom plan view of Fig. 1.

I claim:

The ornamental design for a cocktail fork, as shown.

AARON H. FISHMAN.
